AGITATOR FOR WASHING MACHINES

Charles C. Scheele, Syracuse, N. Y., assignor to
Easy Washing Machine Corporation, Syracuse, N. Y., a corporation of Delaware

Application March 5, 1936, Serial No. 67,333

6 Claims. (Cl. 68—134)

My invention relates to washing machines and, more particularly, to a novel agitator or dolly therefor.

An object of my invention is to provide an agitator for a washing machine which is adapted to cleanse the clothes thoroughly and in a minimum length of time.

Another object of my invention is to provide an agitator for a washing machine which is adapted to oscillate the clothes backward and forward in accordance with the oscillations of the agitator and which, at the same time, causes an inward and outward movement of the clothes to and from the side walls of the vat.

My invention further contemplates the provision of an agitator having a plurality of blades, the blades being dissimilar in shape, one of the blades being relatively wide at its mid-portion while the others of said blades are relatively narrow at their mid-portions.

More specifically, my invention contemplates the provision of an agitator for a washing machine having a plurality of blades extending preferably radially of a central post and preferably 25 extending from substantially the bottom of the vat to the normal surface level of cleansing fluid, the blades being dissimilar in shape, at least one of said blades being relatively wide at least near its central portion, and the remainder of said 30 blades being relatively narrow near their central portions.

Other objects and advantages of my invention will be more apparent from the following description when taken in connection with the accompanying drawings, in which:

Figure 1 is a view showing the preferred form of my invention and indicating a washing vat in which the agitator is mounted.

Figure 2 is a view taken on the line 2—2 of Figure 1.

Figure 3 is a view taken on the line 3—3 of Figure 1.

Figure 4 is a view taken on the line 4—4 of Figure 1.

Figure 5 is a view, partly in section, showing a modified form of my invention and indicating a washing vat in which the agitator is mounted.

Figure 6 is a view taken on the line 6—6 of Figure 5.

Figure 7 is a view taken on the line 7—7 of Figure 5.

Figure 8 is a view showing another modified form of my invention and indicating a washing vat in which the agitator is mounted.

Figure 9 is a view taken on the line 9—9 of Figure 8.

Figure 10 is a view taken on the line 10—10 of Figure 8.

Figure 11 is a view taken on the line 11—11 of Figure 8.

The agitator of my invention is adapted to be mounted in a vat or tub 11 in which clothes and washing fluid are placed. The washing vat may be of any desired shape, either square or, 10 as shown in the drawings, circular in cross section. The agitator, generally indicated by the numeral 12, is preferably mounted centrally of the vat 11 and is driven by a shaft 13 extending upwardly through the bottom of the vat. The 15 drive shaft 13 may be driven by any suitable mechanism and from any suitable source of power, not necessary to be shown or described herein since such driving mechanism for oscillating the agitator is well known in the art to 20 which this invention applies. Preferably, the shaft is driven in an oscillatory manner so as to drive the agitator through an arc of 180 degrees, more or less, and at a comparatively high rate of speed somewhere between fifty and sixty 25 oscillations per minute.

The shaft 13 extends upward to or above the normal surface level of cleansing fluid, and the agitator 12 is preferably driven by the shaft in the manner described in copending application 30 Serial No. 55,050 filed December 18, 1935, in the name of Peter Eduard Geldhof. A sleeve 14, extending concentric with the agitator shaft 13, provides additional support for the agitator as set forth in said application. 35

The agitator itself comprises a bottom plate or base 15 which is preferably substantially flat and is mounted close to the bottom of the vat. Towards its central portion, as at 15', the base slopes upward and merges into a central up-standing post 16 which rises to or above the normal surface level of cleansing fluid. Near the top of the agitator and marking the normal surface level of cleansing fluid is an annular plate 17 which is formed integral with the agitator 40 and which is preferably somewhat smaller in diameter than the base 15. On the top of the plate 17 is mounted a cap 18 which may be secured to the agitator in any suitable manner. 45

The blades, preferably three in number, 19, 21 50 and 22, extend preferably radially outward from the central post between the base 15 and the top plate 17. In accordance with my invention, the blades are made dissimilar in shape, the blade 19 being relatively wide while the blades 21 and 55

22, although they may be made dissimilar to each other, are preferably made, as shown in the drawings, similar to each other. The outer edge of the blade 19, at its lowermost extremity, as indicated at 23, meets the outer periphery of the base 15, from which point it curves sharply upward and inward to a point 24. From the point 24, the outer edge of the blade curves outward and upward to a point 25 where the blade attains its maximum width, which is approximately at the vertical center of the blade. From the vertical center of the blade, the outer edge of the blade curves upward and inward to a point 27 where the blade attains its minimum width, from which point the outer edge curves slightly outward and upward to merge with the top plate 17 at the point 28 substantially at the periphery thereof.

The outer edges of the blades 21 and 22 meet the outer periphery of the base 15 at 29. From this point, the outer edge of each of the blades extends upward and slightly outward to a point 31. From the point 31, the outer edge of each of the blades curves upward and inward to a point 32 where the blades attain their minimum width, which is substantially at the vertical center of the agitator. From the vertical center of the agitator, the blades extend upward and outward and meet the peripheral edge of the top plate 17 at 33. The blades 21 and 22 thus attain their minimum widths at the vertical center of the agitator, at which point the blade 19 is widest.

When the agitator is oscillated, the clothes and washing fluid are violently agitated in the vat, the action being particularly vigorous perhaps because of the unbalanced condition of the blades. The blade 19, when it rotates in the clockwise direction, causes a movement of the clothes and washing fluid outward towards the side walls of the vat in a clockwise direction. If the agitator had three blades of equal size and shape, such as the agitator shown in Figures 6 and 7 of the above mentioned co-pending Geldhof application, upon reversal of the agitator, this movement in the clockwise direction wou'd be interrupted by a force in the counter-clockwise direction caused by the next adjacent blade. However, because the blade 22 is relatively narrow, when the agitator reverses it only partially counteracts this movement in a clockwise direction. When the blade 19 reverses and rotates in a counterclockwise direction, a slight suction is created behind it which causes the clothes previously thrust outward in a clockwise direction to be drawn inwardly from the side walls of the vat toward the agitator.

The movement of the clothes on the clockwise facing side of the blade 19 is thus somewhat circular in a clockwise direction, the path of movement being from the blade outward in a clockwise direction toward the side walls of the vat and then inward still slightly in a clockwise direction toward the center of the agitator where they are drawn slightly in a counterclockwise direction in behind the blade 19. A similar outward counterclockwise movement of the clothes on the counterclockwise facing side of the blade 19 occurs so that the blade 19, as it oscillates in the vat, causes two currents of clothes and fluid 70 movement which extend outward in a curved path away from the blade 19 in clockwise and counterclockwise directions. The main functions of the blades 21 and 22 are to create cross currents and to keep the clothes and washing fluid, which happen to be in a position in the vat

such as to be effected by them, in a state of agitation. Due to the fact that the blade 19 is much more vigorous in its action because of its greater area, than the blades 21 and 22, the larger proportion of the clothes normally is in 6 that half of the vat through which the blade 19 oscillates.

The agitator of Figures 5 to 7, inclusive, is provided with preferably three blades, 36, 37 and 38. The blade 36 is of considerable width 10 throughout its height. At its bottom edge, the blade extends to the periphery of the base 15, as at 39, from which point the outer edge extends upward and slightly inward to a point 41 where the blade attains its minimum width. The 15 blades 37 and 38, at their bottom edge 42, extend to the periphery of the base 15, from which point the outer edges thereof extend upward and then sharply inward as at 43 to a point 44 below the vertical center of the agitator where they attain 20 their minimum width. From the point 44, the outer edges of the blades 37 and 38 curve upward and outward to a point 46 near the top of the agitator. From the point 46, the outer edges of the blades extend upward and inward and 25 above the point 47 they are the same shape as the blade 36.

The agitator of this modification is provided with a cap 48 which is of somewhat different shape than the cap 18 of the preferred form of 30 the invention. The cap 48 is provided with a substantially bell-shaped dome 49 which houses the connection between the shaft 13 and the agitator through which the agitator is oscillated. From the lower edge 51 of the bell-shaped portion 35 of the cap, the cap extends downward and is shaped in the form of a frustum of a cone as illustrated at 52, the lower edge of which is beaded, as indicated at 53. The inner surface of the portion 52 of the cap may contact with the 40 edges of the blades 36, 37 and 38, as indicated at 54. The frusto-conical portion 52 of the cap 48 is provided with a plurality of closely spaced apertures 56.

The action of the agitator of this modification 45 is somewhat similar to that above described in connection with the preferred form of the invention. The apertures 56 serve to prevent entrainment of cleansing fluid beneath the cap, a constant inward and outward movement of the 50 cleansing fluid occurring through the apertures, the surface of which is preferably at the level of the top of the blades.

The agitator of Figures 8 to 11, inclusive, is provided with a plurality of blades 57, 58 and 59, each of the blades being dissimilar in shape. The lower edge of the blade 57 extends outward to the periphery of the base 15, as at 61, from which point the outer edge extends substantially vertically to the point 62 where it is rounded 60 inward. From 62, the outer edge extends horizontally inward to the point 64. From 64, the outer edge of the blade 57 curves sharply upward and inward to a point 66 where the blade attains its minimum width. From the point 66, 65 the outer edge of the blade curves upward and outward to a point 67 and then inward and upward to meet the outer edge of a plate 68 mounted on the top of the blades. The outer edge of the blade 58, from the point 69 where it meets the 70 periphery of the disk 15, extends vertically upward to the point 71, then curves smoothly inward to the point 72 where it attains its minimum width, which is substantially at the vertical mid-point of the agitator. From the point 72, the 75

outer edge of the blade curves smoothly upward to meet the periphery of the top plate 68 at 73.

The lower edge of the blade 59 extends to the periphery of the base 15 at 74 from which point the outer edge curves upward and inward to the point 76. From the point 76, the outer edge extends upward and outward to the point 77 approximately at the vertical midpoint of the agitator where the blade attains its maximum width. 10 From the point 77, the outer edge curves inward and upward to 78, and then outward and upward to meet the periphery of the top plate at 79. As shown in Figures 9, 10 and 11, in this modification, the blade faces, in horizontal cross section, merge with the center post 16 in a smooth curve, as indicated at 81. The curvature of the faces is such that the adjoining faces of adjacent blades are formed on the arc of the same circle. The blade structure of the agitator thus formed presents smooth surfaces to the clothes. The entire agitator structure, with the exception of a cap 82, similar to the cap 18, may be cast integral, the center being cored out somewhat as indicated at 83.

25 The action of the agitator of this modification, in operation, is somewhat similar to that of the first two modifications, except that it is far more gentle in its action. This is probably due to the absence of sharp angles between the blades and the center post 16 and to the fact that the blades 57 and 59 are both of comparatively large area so that the currents above described, in connection with the description of the preferred form of the invention, are largely broken up.

30 While I have shown the preferred forms of my invention, it will be apparent that various modifications and changes may be made in the form of the agitator and relation of parts thereof without departing from the spirit of the appended claims.

35 I claim:

40 1. An agitator adapted to be mounted for operation in a vat containing clothes and cleansing fluid, said agitator comprising a base, a central portion extending upward from the base substantially to the normal surface level of cleansing fluid in the vat, a plurality of blades extending radially outward from the post, and a plate mounted on the top of the blades and marking the normal surface level of cleansing fluid, at least two of said blades being of dissimilar shape, one of said blades being of substantial width at substantially its vertical center and of lesser width at the top and bottom, and another of said blades being narrow at substantially its vertical center and wider at its top and bottom.

45 2. An agitator adapted to be mounted for operation in a vat containing clothes and cleansing fluid, said agitator comprising a base, a central

portion extending upward from the base substantially to the normal surface level of cleansing fluid in the vat, a plurality of blades extending radially outward from the post and a plate mounted on the top of the blades and marking the normal surface level of cleansing fluid, at least two of said blades being of dissimilar shape, one of said blades being of substantial width at substantially its vertical center and of lesser width at the top and another of said blades being narrow at substantially its vertical center and wider at its top and bottom.

5 3. An agitator adapted to be mounted for operation in a vat containing clothes and cleansing fluid, said agitator comprising a base, a central portion extending upward from the base substantially to the normal surface level of cleansing fluid in the vat, a plurality of blades extending substantially radially outward from the post and a plate mounted on the top of the blades and marking the normal surface level of cleansing fluid, one of said blades being of substantial width throughout substantially its entire height, a second of said blades being narrow at its vertical center and relatively wide at its top and bottom and a third of said blades being wide at the bottom, relatively narrow at a point approaching its vertical center and wide at the top.

20 4. An agitator adapted to be mounted for operation in a vat containing clothes and cleansing fluid, said agitator comprising a central portion extending upward from substantially the bottom of the vat to substantially the normal surface level of cleansing fluid in the vat, a plurality of blades extending outward from the post, one of said blades being of substantial width at substantially its vertical center and of lesser width at the top and another of said blades being narrow at substantially its vertical center and wider at its top and bottom.

25 5. An agitator adapted to be mounted for operation in a vat containing clothes and cleansing fluid, said agitator comprising a central portion and a plurality of blades extending outward from said central portion, and a cap extending over the tops of said blades, said cap having a hood portion extending downward along the outer side edges of the blades.

30 6. An agitator adapted to be mounted for operation in a vat containing clothes and cleansing fluid, said agitator comprising a central portion and a plurality of blades extending outward from said central portion, and a cap extending over the tops of said blades, said cap having a hood portion extending downward along the outer side edges of the blades, said hood having perforations therein.

35 CHARLES C. SCHEELE.
